[57] CLAIM

The ornamental design for a clip for a writing instrument.

DESCRIPTION

FIG. 1 is a front view of my novel clip design showing a central groove extending along the length of the clip;

FIG. 2 is a side view of my clip design showing in phantom line the L-shaped attachment portion of the clip for attaching the clip to a writing instrument;

FIG. 3 is a rear view of my clip design showing in phantom line the L-shaped attachment portion;

FIG. 4 is a bottom view of my clip design showing in phantom line the L-shaped attachment portion;

FIG. 5 is a top view of my clip design showing in phantom line the L-shaped attachment portion; and,

FIG. 6 is a perspective view of my clip design, the attachment portion not being shown.
